(57) **CLAIM**

The ornamental design for a back brace, as shown and described.

DESCRIPTION

FIG. 1 is a perspective view of a back brace showing the new design;

FIG. 2 is a front view thereof;

FIG. 3 is a side view thereof;

FIG. 4 is a side view thereof; and,

FIG. 5 is a back view thereof.

The broken lines showing protruding back elements and back laces illustrate portions of the back brace which form no part of the claimed design.
